STRAINER FOR THE WATER CIRCULATION MECHANISM OF A DISHWASHER

David A. Jellies, Fullerton, Calif., and Raymond A. Krishock, Chicago, Ill., assignors to General Electric Company, a corporation of New York

Filed May 28, 1963, Ser. No. 75,102

Term of patent 7 years

(Cl. D49—1)

FIG. 1

FIG. 2

FIG. 3

FIG. 1 is a top perspective view of a strainer for the water circulation mechanism of a dishwasher, showing our new design;

FIG. 2 is a side elevational view thereof; and

FIG. 3 is a bottom plan view thereof.

The dominant features of our new design reside in the portion shown in full lines.

We claim:

The ornamental design for a strainer for the water circulation mechanism of a dishwasher, substantially as shown and described.
